[57] CLAIM

The ornamental design for a suction-attached antenna mounting apparatus, as shown and described.

DESCRIPTION

FIG. 1 is a perspective view of a suction-attached antenna mounting apparatus showing our new design therefor;

FIG. 2 is a front elevational view therefore;

FIG. 3 is a right side elevational view therefore;

FIG. 4 is a rear elevational view therefore;

FIG. 5 is a top plan view therefore; and,

FIG. 6 is a bottom plan view therefore.

The cord is shown with a bracket for ease of illustration and to show indeterminate length.

FIG. 1

FIG. 4

FIG. 5

FIG. 6
